UNITED STATES PATENT OFFICE.

JOHN S. HOBSON AND LEMUEL F. HOWARD, OF EDGEWOOD PARK, PENNSYLVANIA,
ASSIGNORS TO THE UNION SWITCH & SIGNAL COMPANY, OF SWISSVALE, PENN-
SYLVANIA, A CORPORATION OF PENNSYLVANIA.

RAILWAY SIGNALING SYSTEM.

1,070,130.

Specification of Letters Patent. Patented Aug. 12, 1913.

Application filed January 24, 1911. Serial No. 604,399.

To all whom it may concern:

Be it known that we, JOHN S. HOBSON and LEMUEL F. HOWARD, citizens of the United States, residing at Edgewood Park, in the county of Allegheny and State of Pennsylvania, have invented certain new and useful Improvements in Railway Signaling Systems, of which the following is a specification.

10 Our invention relates to electric signaling systems for electric railways.

The present application is a continuation of our co-pending application Serial No. 583,077, filed Sept. 21, 1910, so far as the 15 subject-matter common to the two applications is concerned.

We will describe several forms of signaling systems embodying our invention, and then point out the novel features thereof in 20 claims.

In the accompanying drawings, Figure 1 is a diagrammatic view showing an electric railway having applied thereto a signaling system embodying our invention. Figs. 2 and 3 are views showing modifications of our 25 invention. Fig. 4 is a view showing on a larger scale one form of apparatus and circuits carried by a car or vehicle and embodying our invention. Figs. 5, 6, 7 and 8 are 30 views similar to Fig. 4 but showing modifications of the apparatus and circuits carried by a car or vehicle and embodying our invention.

Similar reference characters designate 35 similar parts throughout the several views.

Referring now to the first three views, 10, 10 designate the track rails of an electric railway, which railway is provided with a source of propulsion current 6; and a transmission system comprising a feeder conductor 3, trolley wire or third rail 2, and the trackway of the railway. 5, 5 designate reactance coils connecting the feed wire 3 with the trolley wire or third rail 2. 11 designates a car or vehicle which travels along the railway from point to point, and which is provided with a trolley or contact shoe 12 adapted to make electrical contact with the trolley wire or third rail 2. The circuit for 45 the propulsion current from the source 6 to the car 11 may be traced as follows: from source 6 through feed wire 3, reactance coil 5, trolley wire or third rail 2, trolley or con-

tact shoe 12, motors and wheels and axles of car 11, track rail or rails 10 to source 6. 55

The transmission system is divided by insulations in any suitable manner to form block sections. As shown in Fig. 1, the track rails 10, 10 are electrically continuous throughout the length of the system, and the trolley wire or third rail 2 is divided by insulations 9, 9 to form block sections A, B and C. As shown in Fig. 2, one of the track rails 10 is electrically continuous, and the other track rail is divided by insulations 41 65 to form block sections A, B and C, the trolley wire or third rail 2 being correspondingly divided by insulations 9. As shown in Fig. 3, the block sections are formed by dividing both track rails 10, 10 by insulations 41, the track rails of each block section being electrically connected with the track rails of the adjacent sections by means of reactance bonds 14 having electrical connections between their middle points. The 75 trolley wire or third rail 2 is correspondingly divided as in the preceding views by insulations 9.

7 designates a source of alternating signaling current connected with mains 8 which 80 extend throughout the system. When the current delivered by the source of propulsion current 6 is direct, this signaling current may be of any desired frequency, but when the propulsion current is alternating, the 85 signaling current is of a different frequency, preferably higher than that of the propulsion current. For each block section we provide a normally open signal circuit, comprising the corresponding section of the 90 third rail or trolley wire 2 and one or both of the track rails 10 of the block section. Each of these signal circuits is supplied in a suitable manner with alternating current from the mains 8, as for example by means 95 of transformers 13 whose primaries are connected with the mains 8 and whose secondary terminals are connected respectively with the trolley wire or third rail 2 and with one or both track rails 10. Upon the closing 100 of such open signal circuit, a signal or other indication is given on the car. This open signal circuit may be closed at any desired point and by any desired means, and the signal or other indication may be of any desired 105 type. For example, in Fig. 1 the open

signal circuit is closed by means of a circuit controller 16, such as a telegraph key, which may be located in a signal cabin or a station 33. Also in this view the signal or communication given on the car or train comprises a miniature signal 20. In Fig. 2 the open signal circuit is closed by means of a circuit controller 16 operated by a railway signaling device 21 located alongside the trackway and preferably adjacent the entrance end of each block section. The railway signals 21 may be controlled in any desired manner; for example as shown in Fig. 3 they may be controlled by track relays which are in turn controlled by track circuits for the block sections.

Fig. 5 shows a modification of the communication given to the car or train, comprising means for cutting off propulsion current and applying the air brakes when the signaling circuit is open. Another modification shown in Fig. 6 comprises a telegraph instrument 32 for the communication of information or signals to the car or train. Still another modification shown in Fig. 7 comprises a lamp 40 carried by the car or train and adapted to be illuminated when the signal circuit is closed.

Each car or train 11 is provided with an electro-translative device 40, connected in circuit with the wheels and axles and the trolley or contact shoe 12, as for example by connecting it in shunt circuit around the motor 30 as shown more clearly in Figs. 4, 5, 6 and 7.

15 and 17 are condensers connected in circuit with the secondaries of the transformers 13 and with the electro-translative devices 40 respectively, for the purpose of preventing the flow of propulsion current through the signal circuit and through the translative devices when the propulsion current is direct, and for limiting the flow to an inappreciable amount when the propulsion current is alternating.

It will be evident from the foregoing description that when a car or train enters a block section, the electro-translative device may complete the open signal circuit and thus be operated by the signaling current supplied to the signal circuit.

The electro-translative device 40 may be of any desired character and may be employed to give any desired type of signal on the car. As shown in Figs. 1 to 6 this device is an electro-magnetic relay. This relay is constructed to respond to the alternating signaling current in its control of a signaling device, and when the propulsion current is alternating, the relay is constructed to respond to current of the frequency of the signaling current and not to current of the frequency of the propulsion current. As shown in Figs. 1 to 4, an armature 18 of the relay 40 is employed to control a circuit

19 for a miniature signal device 20 carried by the car. In Fig. 5, an armature 18^a of the relay 40 is included in the circuit of the propulsion current for the car motors 30, and another armature 18^b of the same relay is included in circuit with an electro-magnetic valve device which controls the application of air brakes to the car. As here shown, the propulsion circuit is closed and the brakes held released only while the relay 40 is energized, but we do not desire to limit ourselves to this specific arrangement of control. When desirable, the relay 40 in any of the arrangements shown may be of a "slow-acting" type as indicated in Fig. 8 in order to prevent its armature or armatures from opening and thus operating the signaling devices controlled thereby when the car passes an insulation in the transmission system; that is, the relay may be so constructed as to hold its armature closed for a suitable period of time after the opening of the energizing or signal circuit. Several methods for accomplishing this purpose are well known in the art and need not be explained here. The arrangements shown in Fig. 8 is in other respects similar to that shown in Fig. 4.

In Fig. 6, the armature 18 of the relay 40 controls the circuit of a telegraph instrument 32 or other similar device for the transmission of signals to a car or train. In Fig. 7, the electro-translative device 40 is a lamp which may be employed to transmit signals of any desired nature to the motorman or other person on the car or train.

It will be evident that when the signal circuits are controlled by circuit controllers operated by fixed signals located along the trackway, the indications of the fixed signals will be repeated by the miniature signal 20 carried by the car, thus avoiding the necessity for fixed "distant" signals, and providing a means for indicating to a person on a car the positions of the fixed signals during foggy weather.

Whenever we have in any of the claims used the phrase "a car traveling along the railway" or "as the car travels along the railway," it will be understood of course that such phrases do not mean that the car must necessarily be moving at all times in order to come within the scope of our invention. Obviously signals may be communicated to a car at any point along the railway, and irrespective of whether the car is moving or standing still. Also whenever we have used the term "electro-translative device" it is to be considered as a term broad enough to cover either a signaling device of any nature, or a medium by which a local circuit may be controlled, which local circuit may include any type of signaling device, such for example as a miniature signal, an electric light, a telegraph instrument, or a de-

vice for controlling the propulsion power and the air brakes of a car.

Having thus described our invention, what we claim is:

- vice for controlling the propulsion power and the air brakes of a car.

Having thus described our invention, what we claim is:

5 1. In an electric railway, a source of propulsion current, a transmission system therefor formed in part by an outgoing feeder conductor, a third rail or trolley, and the trackway of the railway; a plurality of 10 block sections formed by insulations in the transmission system, a source of alternating signal current, open signal circuits each including the third rail or trolley and a track rail of a block section, a car traveling along 15 the railway, a contact carried by said car for engagement with the third rail or trolley, an electro-translative device carried by said car and connected with the wheels and axles and the contact thereof; and 20 adapted to close the open signal circuits as the car travels along the railway whereby the said translative device is operated, and means located along the railway for controlling the open signal circuits.

25 2. In an electric railway, a source of propulsion current, a transmission system therefor formed in part by an outgoing feeder conductor, a third rail or trolley, and the trackway of the railway; a plurality of 30 block sections formed by insulations in the transmission system, a source of alternating signal current, an open signal circuit for each block section formed by connecting the source of alternating signal current with 35 the third rail or trolley and a track rail of the block section, a car traveling along the railway, a contact carried by said car for engagement with the third rail or trolley; an electro-translative device carried by said 40 car and connected with the wheels and axles and the contact thereof, and adapted to close the open signal circuits as the car travels along the railway whereby the said translative device is operated, and means located along the railway for controlling the open signal circuits.

45 3. In an electric railway, a source of propulsion current, a transmission system therefor formed in part by an outgoing feeder conductor, a third rail or trolley, and the trackway of the railway; a plurality of 50 block sections formed by insulations in the transmission system, a source of alternating signal current, an open signal circuit for each block section formed by connecting the source of alternating current with the third rail or trolley and a track rail of the block section, a car traveling along the railway, a contact carried by said car and adapted for 55 engagement with the third rail or trolley; an electro-translative device carried by the car and connected with the wheels and axles and the contact thereof, and adapted to close each open signal circuit as the car travels along the railway whereby the translative device carried by the car is operated, and means located along the railway for controlling the open signal circuits.

60 4. In an electric railway, a source of propulsion current, a transmission system therefor formed in part by an outgoing feeder conductor, a third rail or trolley, and the trackway of the railway; a plurality of 65 block sections formed by insulations in the transmission system, a source of alternating signal current, an open signal circuit for each block section formed by connecting the source of alternating current with the third rail or trolley and a track rail of the block section, a car traveling along the railway, a contact carried by said car and adapted for 70 engagement with the third rail or trolley; an electro-translative device carried by the car and connected with the wheels and axles and the contact thereof, and adapted to close each open signal circuit as the car travels along the railway whereby the translative device carried by the car is operated, and means located along the railway for controlling the open signal circuits.

75 5. In an electric railway, a source of propulsion current, a transmission system therefor formed in part by an outgoing feeder conductor, a third rail or trolley, and the trackway of the railway; a plurality of 80 block sections formed by insulations in the transmission system, a source of alternating signal current, an open signal circuit for each block section formed by connecting the source of alternating current with the third rail or trolley and a track rail of the block section, a car traveling along the railway, a contact carried by said car and adapted for engagement with the third rail or trolley, an electro-translative device carried by the car and connected with the wheels and axles and the contact thereof, and adapted to close each open signal circuit as the car travels along the railway whereby the translative device carried by the car is operated, and means located along the railway for controlling the open signal circuits.

85 6. In an electric railway, a source of propulsion current, a transmission system therefor formed in part by an outgoing feeder conductor, a third rail or trolley, and the trackway of the railway; a plurality of 90 block sections formed by insulations in the transmission system, a source of alternating signal current, an open signal circuit for each block section formed by connecting the source of alternating current with the third rail or trolley and a track rail of the block section, a car traveling along the railway, a contact carried by said car and adapted for engagement with the third rail or trolley, an electro-translative device carried by the car and connected with the wheels and axles and the contact thereof, and adapted to close each open signal circuit as the car travels along the railway whereby the translative device carried by the car is operated, and means located along the railway for controlling the open signal circuits.

95 7. In an electric railway, a source of propulsion current, a transmission system therefor formed in part by an outgoing feeder conductor, a third rail or trolley, and the trackway of the railway; a plurality of 100 block sections formed by insulations in the transmission system, a source of alternating signal current, an open signal circuit for each block section comprising the third rail or trolley and a track rail of the said section, means for impressing the said signal current on said open signal circuit, a car traveling along the railway, a contact carried by said car for engaging the third rail or trolley; an electro-translative device carried by the car and connected with the wheels and axles and the contact thereof whereby the said device may close each open signal circuit as the car travels along the railway and may be operated by the signaling current supplied to said circuit, and circuit controllers located along the railway for controlling the open signal circuits and thereby controlling the electro-translative device carried by the car.

105 8. In an electric railway, a power transmission system comprising a third rail or trolley and the trackway of the railway; a plurality of block sections formed by insulations in the transmission system, an open signal circuit for each block section formed in part by the third rail or trolley and a track rail of the block section, a source of signaling current, means for supplying the signaling current to each signal circuit,

- 4 a car traveling along the railway, a contact carried by said car for engagement with the third rail or trolley; an electro-translative device carried by the car and connected with the wheels and axles and with the contact thereof, and adapted to complete the open signal circuits as the car proceeds along the railway whereby said device may be energized from the said signal circuits, and means located along the railway for controlling the signal circuits.
- 5 7. In an electric railway, a power transmission system comprising a third rail or trolley and the trackway of the railway, a plurality of block sections formed by insulations in the transmission system, an open signal circuit for each block section formed in part by the third rail or trolley and a track rail of the block section, a source of 10 signaling current, a transformer for each block section having its primary connected with the source of signaling current and its secondary with the signal circuit of the block section, a car traveling along the railway, a contact carried by said car for engagement with the third rail or trolley; an electro-translative device carried by the car and connected with the wheels and axles and with the contact thereof, and adapted to 15 complete the open signal circuits as the car proceeds along the railway whereby said device may be energized from the said signal circuits, and means located along the railway for controlling the signal circuits.
- 20 8. In an electric railway, a transmission system comprising a third rail or trolley and a track rail of the railway, a plurality of block sections formed by insulations in the transmission system, a source of alternating signaling current, a transformer for each block section having its primary connected with the source of signaling current and its secondary terminals connected respectively with the third rail or trolley and 25 a track rail of the block section, a car traveling along the railway, a contact carried by the car for engagement with the third rail or trolley; an electro-translative device carried by the car and connected with the wheels and axles and the contact thereof, and adapted to be energized by the signal current of the block sections, and a circuit controller for each block section located along the railway for controlling the supply of signaling current for the block sections.
- 30 9. In combination an electric railway comprising track rails and a third rail or trolley wire, isolated track circuits each formed in part by sections of the two track rails of the railway, a source of signaling current for each of said track circuits, visual signals controlled therefrom, a vehicle traveling along the railway, a signaling device carried by the vehicle, normally open circuits formed in part by the track rails of the trackway and the third rail or trolley wire, a source of signaling current for each of said circuits and having a path through the vehicle for operating the signaling device of the vehicle, and means for controlling said open circuits operated by the visual signals.
- 35 10. In an electric railway propulsion and signal system, roadway signals and cab signals carried by vehicles, cab signal controlling devices on the vehicles, three sources of current, one source for propelling vehicles traveling along the railway, one for controlling the roadway signals and one for controlling the cab signals; the second and third sources differing in character from the first source; three sets of circuits namely a propulsion circuit, roadway signal controlling circuits and cab signal controlling circuits, 40 said circuits comprising two sets of conductors, namely, a third rail or trolley and the trackway, the third rail or trolley constituting a part of the first and third of said circuits and the track rails constituting a part of all three circuits; means on the vehicle for preventing the propulsion current from passing and for permitting the cab signal controlling current to pass through the cab signal controlling device; insulations for isolating the roadway signal controlling circuits and means for rendering the trackway continuous for the power current and for the signaling current operating the signal device on a vehicle.
- 45 11. In combination a railway, a source of power current for vehicles traveling therealong, a power transmission system for said source comprising a third rail or trolley and the trackway of the railway, signal controlling track circuits of which the rails of the trackway form both sides, a source of signaling current for each of said track circuits, visual signals controlled therefrom, a vehicle, a signaling device carried thereby, normally open signaling circuits formed in part by the track rails, the third rail or trolley and the vehicle, and a source of signaling current for each of said open signaling circuits whereby the signaling device carried by the vehicle may be operated as the vehicle travels along the railway.
- 50 12. In combination a railway, a source of power current, a power transmission system therefor comprising a third rail or trolley and the trackway of the railway, signal controlling track-circuits of which the rails form both sides, a source of signaling current for each of said track circuits, visual signaling devices located along the railway and controlled by the signaling current in the track circuits, a vehicle traveling along the railway, an electro-translating device carried by the vehicle for giving a signal to the driver thereof, normally open signal cir-

cuits of which the third rail or trolley and the trackway of the railway each form one side, a source of signaling current for each normally open signal circuit and a contact 5 device carried by the car adapted to complete the open signal circuits successively as the car proceeds along the railway whereby said electro-translative device may be operated, and means operated by the visual signaling devices for controlling the normally open circuits.

13. In an electric railway, a power transmission system comprising a third rail or trolley and the trackway of the railway; a 15 plurality of block sections formed by correlated insulations in the two sides of the transmission system; signal means along the railway associated with each insulated block section of the track rails; an open signal circuit for each block formed in part by the third rail or trolley and a track rail of the block section; a source of signaling current; means for supplying the signaling current to each signal circuit; a car traveling along 20 the railway; a contact carried by said car for engagement with the third rail or trolley; an electro-translative device carried by the car, connected with the wheels and with the contact device thereof and adapted to 25 receive the current from said source of signaling current as the car proceeds along the railway, whereby said device may be energized from successive insulated sections; and means operated by said fixed signal devices 30 controlling the operation of said signal circuits.

14. In an electric railway; a power transmitting system comprising a third rail or trolley and the trackway of the railway; 40 signal controlling track circuits of which the rails form both sides; signaling devices along the railway controlled by said track circuits, normally open signal circuits of which the trackway and the third rail or

trolley each form one side; means for supplying signaling current to each normally open signal circuit; a car traveling along the track way; a contact carried by said car for engagement with the third rail or trolley; an electro-translative device carried by 50 the car and connected with the wheels and axles and with the contact device thereof and adapted to complete the open signal circuits successively as the car proceeds along the railway, whereby said device may be energized from the said signal circuits; and means operated by said track circuit signaling devices for controlling the normally open signal circuits.

15. In an electric railway a trackway divided into block sections and a third rail or trolley also divided into block sections; inductive connections rendering said trackway and third rail or trolley respectively capable of transmitting power currents, but of isolating signal currents; a closed signal circuit for each block of which the trackway rails constitute both sides; an open signal circuit for each block of which the trackway and the third rail or trolley each constitute one side; means for supplying signaling current to both of said signal circuits; a car traveling along the trackway; a contact device carried by said car; an electro-translative device connected between the wheels 65 and contact device of said car; and means controlled by said closed signal circuits for controlling said open signal circuits and the electro-translative device when connected therein by the presence of the car. 70

In testimony whereof we affix our signatures in presence of two witnesses.
